J. McMULLEN.
REINFORCED CAR END.
APPLICATION FILED MAR. 10, 1920.

1,412,210.

Patented Apr. 11, 1922.

UNITED STATES PATENT OFFICE.

JOHN McMULLEN, OF BUFFALO, NEW YORK, ASSIGNOR TO CHICAGO-CLEVELAND CAR ROOFING COMPANY, OF CHICAGO, ILLINOIS, A CORPORATION OF ILLINOIS.

REINFORCED CAR END.

1,412,210.

Specification of Letters Patent. Patented Apr. 11, 1922.

Application filed March 10, 1920. Serial No. 364,661.

To all whom it may concern:

Be it known that I, JOHN McMULLEN, a citizen of the United States, residing in Buffalo, in the county of Erie and State of New York, have invented a new and useful Improvement in Reenforced Car Ends, of which the following is a specification.

The invention relates to reenforced car ends, and has for its object to strengthen the end of a car against horizontal strains, so as to preserve its proper shape in use; and to apply the reenforcement in such manner that it will not obstruct any part of the interior of the car body. A further object is to provide a reenforcement which is of a unitary character and may be applied at the time of making repairs to car bodies already constructed. A further object of the invention is to connect the reenforcing frame with the exterior metal members of the car end so as to join them directly with the side plates of the roof frame at points on said side plates which are at a considerable distance from the end of the car.

With such objects in view, as well as other advantages which may be incident to the use of the improvements, the invention consists in the parts and combinations thereof hereinafter set forth and claimed, with the understanding that the several necessary elements constituting the same may be varied in proportions and arrangement without departing from the nature and scope of the invention.

In order to make the invention more clearly understood there are shown in the accompanying drawings means for carrying the same into practical effect, without limiting the improvements, in their useful applications, to the particular constructions which, for the purpose of explanation, have been made the subject of illustration. In the said drawings:

Fig. 1 is a plan view of an end portion of a car body, partly in section on line 1—1 of Fig. 2, and embodying the invention.

Fig. 2 is an elevation of the car end.

Fig. 3 is a vertical sectional view on line III—III of Fig. 1.

Fig. 4 is a vertical sectional view on line IV—IV of Fig. 1.

Fig. 5 is a vertical sectional view on line V—V of Fig. 1.

Referring to the drawings, 1 indicates

car roof frame, 3 the side sheathing and 4 the end sheathing.

Exterior to the end sheathing are arranged vertical Z-bars 5 secured to the car body frame and to the end sheathing in a known manner by bolts 6.

The reenforcing end frame does or may comprise the following structural elements or their equivalents: 7 indicates a transverse steel bar or supplemental end plate arranged in the roof frame near the end plate 2 and having secured to its ends gusset plates 8 which brace against the inner faces of the side plates and aid in maintaining the angular shape of the car against torsional strains in horizontal planes. The bar 7 is preferably of channel or L-shape in cross section having its vertical web or flange 9 depending against the inner face of the end plate 2. 75

The usual end frame of the car thus held in shape and stiffened by the bracing elements 7 and 8, is connected with the two side frames at points remote from the end frame by diagonal tie members 10. These members are shown as strong round rods which pass through the flanges 9, end plate 2, end sheathing 4 and Z-bars 5. At their other ends said rods pass through the angle bracket plates 11 which are securely bolted to the inner faces of the side plates. The ends of the rods 10 are screw-threaded and fitted with nuts 13 which can be drawn tightly against the outer faces of the Z-bars and against the bracket plates 11 to give the proper shape to the end of the car body and thereafter maintain it. 80 85

The diagonal direction is given to the rods 10 by bends 12 therein which are formed where they pass through the flange 9 of the end bar. 90 95

The steel frame above described is supplemental to the usual car frame and is arranged out of the way near the roof of the car. It is securely anchored to the entire car end by means of the Z-bars 5, end bar 7 and brace members 8, and is also strongly anchored to the side plates of the car frame at points remote from the end of the car. 100 105

Said shaping and stiffening frame may usually be applied to car bodies after they have been constructed or when they are being repaired.

The gusset plates 8 are formed with ver- 110

tical flanges 14 by which they are bolted to the side plates of the car frame, and with horizontal flanges 15 which extend inwardly along the end portions of the supplemental 5 end plate 7 to which they are securely riveted or bolted (Fig. 1).

The bracket plates 11 are formed with vertical flanges 16 by which they are bolted firmly to the inner faces of the side plates 10 of the car frame, and with vertical flanges 17 which are located at right angles to the tie members 10 and are perforated for the passage of said tie members, so that the nuts 18, when in place, bear against the outer 15 sides of said flanges 17 (Fig. 3).

What is claimed is—

1. The combination, with a car end frame, of a supplemental steel frame comprising an end bar extending for substantially the 20 width of the car and diagonal members which are separate from and engage said end bar and extend across the angles in which gusset plates are located, said steel frame being arranged horizontally and in engagement with the upper parts of the side and end frames of the car and connected therewith, and comprising said gusset plates which are separate from said end bar and are connected with the same and with the 30 side plates of the car frame.

2. The combination, with a car end frame having exterior metal bars, and side plates of the car frame, of a supplemental steel frame comprising a supplemental end plate 35 arranged at the inner side of the car end plate and attached thereto and extending from side plate to side plate, gusset plates having vertical flanges attached to the inner faces of the side plates and having horizontal flanges which extend along the end 40 portions of the supplemental end plate and are attached thereto, and diagonal tie members connected with the side plates at a distance from the end of the car and connected 45 with the supplemental end plate and with the car end plate.

3. The combination, with a car end frame having exterior metal bars having apertured flanges, and side-frames, of a supplemental 50 steel frame comprising diagonal tie members arranged horizontally and connected with the upper parts of said side and end frames and bent to form longitudinal ends

which pass through the flange apertures to the outer side of said exterior metal bars. 55

4. The combination, with a car end frame having exterior metal bars, and side frames, of a supplemental steel frame comprising a supplemental end plate extending for substantially the width of the car and diagonal 60 members, and arranged horizontally and in engagement with the upper parts of said side and end frames and connected therewith and with said exterior bars, the ends of said diagonal members being extended 65 through and to the outer side of said supplemental end plate and attached thereto.

5. The combination, with a car end frame having exterior vertical Z-bars, and side frames, of a supplemental steel frame comprising a supplemental end plate extending for substantially the width of the car and diagonal 70 members, and arranged horizontally and in engagement with the upper parts of said side and end frames and connected 75 therewith and with said Z-bars, and bracket plates arranged at an angle to and separate from said diagonal members and formed with vertical flanges attached to the inner faces of the car side plates and with vertical flanges extending transversely to said diagonal members and attached to the latter. 80

6. In a car end frame, in combination, side plates, an end plate, a supplemental end plate extending for substantially the width 85 of the car and having means whereby it is braced against the side plates, and diagonal tie members which pass through the car end plate and are secured at their ends to the end plate near the roof of the car and are secured at their other ends to the side plates 90 at points remote from the car end.

7. In a car end frame, in combination, side plates, an end plate, vertical Z-bars secured on the exterior of the car end, a supplemental end plate having separate gusset plates whereby it is braced against the side plates, and diagonal tie members which are secured at their ends directly to said Z-bars near the roof of the car and are secured at their other ends to the side plates at points remote from the car end, whereby stresses are transmitted by said gusset plates and tie members from the car end to the side plates at their ends and at points remote from their ends. 95

JOHN McMULLEN.
